UNITED STATES PATENT OFFICE.

FRANK GRAD, OF CARNEGIE, OKLAHOMA.

DESIGN FOR A BOTTLE.

Application filed July 25, 1927. Serial No. 22,882. Term of patent 14 years.

To all whom it may concern:

Be it known that I, FRANK GRAD, a citizen of the United States, residing at Carnegie, in Caddo County, State of Oklahoma, have invented a new, original, and ornamental Design for Bottles, of which the following is a specification, reference being had to the accompanying drawing, forming part thereof.

The figure is an elevational front view of the bottle showing my new design.

I claim:

The ornamental design for a bottle, as shown.

FRANK GRAD.
